RAILWAY SIGNALING

Original Filed April 21, 1921

INVENTOR

F. H. Nicholson
A. Z. Venecill

 ATTORNEY

UNITED STATES PATENT OFFICE.

FRANK H. NICHOLSON, OF PHILADELPHIA, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY SIGNALING.

Original application filed April 21, 1921. Renewed January 22, 1923, Serial No. 463,234. Divided and this application filed November 17, 1924. Serial No. 750,293.

My invention relates to railway signaling, and particularly to signaling of the type wherein roadside signals are controlled in accordance with the presence and absence of

5 trains through the medium of track circuits.

I will describe one form of signaling apparatus embodying my invention, and will then point out the novel features thereof in claims.

10 The present case is a division of my co-pending application, Serial No. 463,234, filed Jan. 22, 1923, as a renewal of my original application, filed April 21, 1921, for railway signaling.

15 The accompanying drawing is a diagrammatic view showing one form of signaling apparatus embodying my invention.

Referring to this drawing, the reference characters E and E^a designate the track rails 20 of a stretch of railway track over which traffic normally moves in the direction indicated by the arrow. These track rails are divided, by means of insulated joints 2, into a plurality of successive track sections A—B, 25 B—C, etc., and each section is provided with a roadside signal which is designated by the reference character S with an exponent corresponding to the location. As shown in the drawing, each of these signals is of the 30 semaphore type, adapted to indicate "Stop", "Caution" or "Proceed" according as the semaphore blade is in the horizontal, inclined or vertical position.

Each track section is provided with a 35 track circuit comprising a transformer designated by the reference character T with an exponent corresponding to the location, the secondary of which transformer is connected across the rails adjacent the exit end 40 of the section. The primary of each transformer T is supplied with alternating current from some suitable source such as an alternator 4, over a transmission line 3. As here shown the supply of such current to each

45 transformer is controlled by a pole changer operated by the adjacent signal and designated by the reference character P with a suitable exponent. Each pole changer is operated during the movement of the signal 50 between stop and caution positions, and so the section in the rear of an occupied section is supplied with alternating current of one relative polarity, which I will term the

"reverse" polarity, whereas all other sections are supplied with current of the opposite 55 relative polarity, which I will term "normal" polarity.

Each track circuit also comprises a transformer designated H with a suitable exponent, the primary of which is connected 60 across the track rails at the entrance end of the section, and the secondary of which controls the corresponding signal S through the medium of apparatus which I will now describe.

65 Each signal S is controlled directly by a relay designated by the reference character F with a suitable exponent. Each of these relays is of the usual direct current type, having a neutral armature responsive to the 70 presence and absence of current, and a polarized armature responsive to the direction of flow of current through the relay winding. The winding for this relay is in two sections, designated 27 and 27^a, which sections are 75 connected at the middle so that the relay is what may be termed a differential polarized relay. That is, if current flows into the relay through wire 28 and passes through the upper section 27, the neutral armature will be closed and the polarized armature will be 80 swung to one extreme position. If current enters the relay through wire 28, but flows through the lower section 27^a, the neutral armature will still be closed but the polarized armature will be swung to its opposite 85 extreme position.

The supply of energy to each relay F is controlled by two electron tubes D' and D^a associated therewith and each comprising, as 90 usual, a filament 5, a grid 6, and a plate 7.

95 Each section is further provided with a transformer designated by the reference character J with an appropriate exponent. The primary 15 of each such transformer J is constantly supplied with alternating current from transmission line 3.

100 Referring particularly to location A, the signal S^A is provided with a caution indication circuit which passes from a secondary 29 of transformer J^A through wire 30, neutral contact 31 of relay F^A, wire 32, operating mechanism of signal S^A, and wire 33 to secondary 29. The signal is also provided with a proceed indication circuit which 105 passes from secondary 29, through wire 30,

contact 31 of relay F^A , wire 34, polarized contact 35 of relay F^A , wire 36, operating mechanism of signal S^A , and wire 33 to secondary 29. The caution indication circuit is, of course, closed when either winding of relay F^A is energized, but the proceed indication circuit is closed only when contact 35 is swung to the left, and this occurs only when the upper winding 27 is energized. The controlling circuits for each of the remaining signals are the same as those for signal S^A .

Still referring to the apparatus associated with signal S^A , the relay F^A is supplied with current from a secondary 16 of the transformer J^A , and this supply is governed by the two electron tubes D' and D^2 associated therewith, which in turn are controlled by the transformer H^A . The electron tube filaments 5 are heated by a secondary 8 on transformer J^A , these filaments as here shown being connected in series. Tube D' is provided with a grid circuit which passes from the right hand terminal of secondary 23 of transformer H^A , through wire 25, grid 6 and filament 5 of tube D' , and wires 38 and 24 to the middle point of secondary 23. Similarly, the grid 6 of tube D^2 is connected with the left hand terminal of secondary 23 through a wire 26, while the filament 5 of this same tube is connected with the middle point of secondary 23 by wires 41, 24^a and 24. It will be seen from the foregoing, that at any given instant the polarities of the grids 6 of the two tubes D' and D^2 are opposite; that is, when the grid of tube D' is positive with respect to its associated filament, the grid of tube D^2 is negative with respect to its associated filament.

The circuit for the secondary 16 of transformer J^A comprises two branches, one of which includes section 27 of the winding of relay F^A and electron tube D' , whereas the other branch includes section 27^a of the relay winding and electron tube D^2 . First considering tube D' , the complete plate circuit for this tube is from the left hand terminal of secondary 16, through wire 28, section 27 of the winding of relay F^A , wire 37, tube D' , and wires 38, 24^a and 39 to right hand terminal of secondary 16. As for tube D^2 , the complete plate circuit is from secondary 16, through wire 28, section 27^a of the winding of relay F^A , wire 40, tube D^2 and wires 41 and 39 to secondary 16.

The primary 15 of transformer J^A is connected with the transmission line 3, and the parts of the apparatus are so adjusted that the plate circuit voltages in tubes D' and D^2 are either substantially in phase with, or displaced substantially 180° from the grid voltages applied to these tubes by transformer H^A . It follows that when pole changer P^B is in one position, the grid 6

of tube D' will be positive with respect to the filament at the same instant that the plate 7 of this tube is also positive with respect to the filament. When this is the case, current will flow freely from secondary 16 through tube D' and winding section 27 of relay F^A , but substantially no current will flow through tube D^2 and section 27^a, because the grid of this tube is negative with respect to the filament at the instant that the plate 7 is positive with respect to the filament. The arrangement is such that tube D' is thus conductive when signal S^B indicates caution or proceed, that is, when track section B—C is unoccupied. When pole changer P^B is reversed, however, it will be obvious that current will flow freely through tube D^2 but that substantially no current will flow through tube D' , so that winding section 27^a of relay F^A will be supplied with current but section 27 will be de-energized. It will be seen, therefore, that the relay F^A is energized only when track section A—B is unoccupied, and that the polarized armature of relay F^A is closed or open according as section B—C is unoccupied or occupied.

As shown in the drawing, track section C—D is occupied by a car or train W, so that the supply of current to transformer H^C is discontinued. The potential in the electron tube plate circuits due to transformer J^C is relatively low, so that the currents flowing through the windings of relay F^C are small when the grid circuits of tubes D' and D^2 are de-energized. Furthermore, the currents that flow through winding 27 and 27^a of relay F^C neutralize each other in their effect upon neutral armature 31, because these currents are substantially equal, and they flow in opposite directions through the relay winding. It should also be noted that when transformer H^C is de-energized, that is, when the grids 6 are de-energized, the small currents in the plate circuits due to secondary 16 will flow on the positive half wave only, there being no flow in the opposite direction on the consecutive half waves. Relay F^C is, therefore, open so that signal S^C indicates stop. Pole changer P^C , which is operated by signal S^C , is in such position as to supply current of reverse relative polarity to the rails of section B—C. The result of this is that tube D^2 at signal S^B is rendered conductive, so that winding section 27^a of relay F^B is supplied with current. This causes energization of relay F^B in such direction that its polarized contact 35 is open, with the result that signal S^B indicates caution. The pole changer P^B is therefore in such position that current of normal relative polarity is supplied to the rails of section A—B, so that tube D' for this section is rendered conductive. This causes winding section 27 of

relay F^a to be energized, so that polarized contact 35 of this relay is closed, with the result that signal S^a is in the proceed position.

5 Although I have herein shown and described only one form of signaling apparatus embodying my invention, it is understood that various changes and modifications may be made therein within the scope 10 of the appended claims without departing from the spirit and scope of my invention.

Having thus described my invention, what I claim is:

1. In combination, a section of railway 15 track, a track circuit for said section including a source of current reversibly connected with the rails; two electron tubes each having a heated filament, a grid and a plate; a grid circuit for each tube energized from said track circuit in such manner that when the grid of either tube is positive with respect to its filament the grid of the other tube is negative with respect to its filament; a plate circuit connected with 20 a source of alternating current and provided with two branches including said two tubes respectively; a polarized relay having two differential windings included in the two branches of said plate circuit; and signaling 25 means controlled by said relay.

2. In combination, a section of railway 30 track, a track circuit for said section including a source of current reversibly connected with the rails; two electron tubes each having a heated filament, a grid and a plate; a grid circuit for each tube energized from said track circuit in such manner that when the grid of either tube is positive with respect to its filament the grid 35 of the other tube is negative with respect to its filament; a plate circuit connected with a source of alternating current and provided with two branches including said two tubes, respectively; and signaling means for giving 40 one indication or another according as a substantial current flows in one branch or the other of said plate circuit.

3. In combination, a section of railway 45 track, a track circuit for said section including a source of current reversibly connected with the rails; two electron tubes each having a heated filament, a grid and a plate; a grid circuit for each tube energized from said track circuit in such manner that when the grid of either tube is positive with respect to its filament the grid of the other tube is negative with respect to its filament; a plate circuit connected with a source of alternating current 50 and provided with two branches including said two tubes, respectively; a plate circuit for each tube including a source of alternating current substantially in phase with, or displaced 180° from the track circuit 55 current; and signaling means for giving one

indication or another according as a substantial current flows in one of said plate circuits or the other.

4. In combination, a section of railway 60 track, a track circuit for said section including a source of alternating current reversibly connected with the rails, two electron tubes, a grid circuit for each tube energized from said track circuit, a plate circuit for each tube, said plate circuits being so connected that one plate circuit or the other is conductive according to the relative polarity of the track circuit current, a polarized relay having two differential windings included in said two plate circuits respectively, and signaling means controlled by said relay.

5. In combination, a section of railway 65 track, a track circuit for said section including a source of alternating current reversibly connected with the rails, two electron tubes, a grid circuit for each tube energized from said track circuit, a plate circuit for each tube, said plate circuits being so connected that one plate circuit or the 70 other is conductive according to the relative polarity of the track circuit current, and signaling means controlled by said plate circuits.

6. In combination, a section of railway 75 track, a track circuit for said section including a source of alternating current reversibly connected with the rails, two electron tubes each having a grid circuit arranged to receive energy from the track circuit, two plate circuits one for each said tube, a polarized relay controlled by said plate circuits in accordance with the relative polarity of the track circuit current, and signaling means controlled by said polarized relay.

7. In combination, a section of railway 80 track, a track circuit for said section including a source of energy reversibly connected with the rails, two other circuits for said section, means controlled by the relative polarity of the track circuit current in said track circuit for varying the resistances of said other circuits, a polarized relay controlled in accordance with the resistances 85 of said two other circuits, and signaling means controlled by said relay.

8. In combination, a section of railway 90 track, a track circuit for said section including a source of energy reversibly connected with the rails, two other circuits for said section, means controlled by the relative polarity of the track circuit current in said circuit for varying the resistances of 95 said other circuits, a polarized relay comprising two differential winding sections included in said two other circuits respectively, and signaling means controlled by said relay.

9. In combination, a section of railway 100

track, a track circuit for said section including a source of energy reversibly connected with the rails, a polarized relay having two differential windings, a first electron tube having a grid circuit receiving energy from said track circuit and adapted to supply current to one said winding when the track circuit current is of one relative polarity, a second electron tube having a grid

circuit receiving energy from the track circuit and adapted to supply current to the remaining relay winding when the track circuit current is of the other relative polarity, and signaling means controlled by said relay.

In testimony whereof I affix my signature.

FRANK H. NICHOLSON.
